Primary Examiner — Philip S Hyder*(74) Attorney, Agent, or Firm* — Scott B. Markow(57) **CLAIM**

The ornamental design for a torsion bit, as shown and described.

DESCRIPTION

FIG. 1 is a perspective view of a torsion bit.

FIG. 2 is a left view of the torsion bit of FIG. 1.

FIG. 3 is a right view of the torsion bit of FIG. 1.

FIG. 4 is a front view of the torsion bit of FIG. 1.

FIG. 5 is a rear view of the torsion bit of FIG. 1.

FIG. 6 is a top view of the torsion bit of FIG. 1; and,

FIG. 7 is a bottom view of the torsion bit of FIG. 1.

The broken lines depict portions of the torsion bit in which the design is embodied that are not considered part of the claimed design.
